UNITED STATES PATENT OFFICE.

NOEL S. DUNBAR, OF NEW YORK, N. Y., ASSIGNOR, BY MESNE ASSIGNMENTS, TO
SPLITDORF RADIO CORPORATION, OF NEWARK, NEW JERSEY.

DESIGN FOR A RADIOCABINET.

Application filed January 20, 1928. Serial No. 24,949. Term of patent 3½ years.

To all whom it may concern:

Be it known that I, NOEL S. DUNBAR, a citizen of the United States, and a resident of New York, borough of Manhattan, and State of New York, have invented a new, original, and ornamental Design for a Radiocabinet, of which the following is a specification, reference being had to the accompanying drawings, forming part thereof, of which—

Fig. 1 is a front perspective view of a

radiocabinet embodying my design showing the closure of the instrument compartment in the closed position.

Fig. 2 is a front perspective view of a radiocabinet embodying my design showing the closure of the instrument compartment in the open position.

I claim:

The ornamental design for a radiocabinet, as shown.

NOEL S. DUNBAR.
